United States Patent Office

Des. 214,209
Patented May 20, 1969

214,209

CONVEYOR

Harry E. Ziegler, Chardon, Ohio, assignor to May-Fran
Manufacturing Co., Cleveland, Ohio, a corporation of
Ohio

Filed Oct. 11, 1967, Ser. No. 8,953

Term of patent 14 years

Int. Cl. D12—05

U.S. Cl. D55—1

FIG. 1

FIG. 2

FIG. 3

FIG. 4

FIG. 5

FIGURE 1 is a perspective view of a conveyor embodying my new design;

FIGURE 2 is a side elevation thereof;

FIGURE 3 is a right end elevation thereof;

FIGURE 4 is a top plan view thereof; and

FIGURE 5 is a side elevation showing the side opposite to that shown in FIGURE 2.

I claim:

The ornamental design for a conveyor, substantially as shown and described.
